HEATING MEANS FOR LOCKS

Brennan B. West, Jr., Cleveland, Ohio

Application December 31, 1937, Serial No. 182,738

6 Claims. (Cl. 70—431)

This invention relates to locks, and has reference more particularly to heating means for locks that are subjected to freezing temperatures.

Locks exposed to the elements, especially those used on automotive vehicles, as on the doors of the passenger, tire and tool compartments of such conveyances, frequently become stuck on account of the congealing of the lubricant therein or the freezing of moisture that has gained access to the locking mechanism, as during rains, snows and washings, and it is with great difficulty and inconvenience that the locks are restored to operative condition. When the tumblers of a cylinder lock become stuck from either of the foregoing causes it is almost impossible to insert the key; and when the key is forced to normal position within the key slot, the tumbler actuating springs are incapable of retracting the key released tumblers to unlocking position with the result that the key is liable to be bent or broken within the lock if undue turning force is applied thereto. Heretofore the situation has been met by crude and makeshift methods of applying heat to the locks, as by holding burning matches under them, pouring hot water over them, applying hot cloths, etc.

The fundamental purpose of my invention is to overcome these difficulties by providing efficient and dependable means associated with a lock for heating the locking mechanism thereby to soften the lubricant or melt the ice obstructing the tumblers or other working parts or otherwise interfering with the action of the lock and thus quickly and conveniently restoring a frozen or stuck lock to normal operating condition.

A more specific object of the invention is to incorporate electrical heating means in locks, desirably in very intimate heat exchanging relation to the locking mechanism, whereby with the minimum current consumption the frozen or stuck locking mechanism may be liberated.

Another object of the invention is to provide a combined latch and lock in which the latch operating member or handle is capable of movement without releasing the latch while the lock is in locking condition, and to associate therewith electrical heating means and a make-and-break device or switch for controlling the supply of current to said means, the same being actuated to close the circuit when the latch operating handle is moved under the aforesaid condition.

The foregoing objects, with others that will appear as this description proceeds, are attained in the illustrative embodiment of the invention shown in the accompanying drawing wherein

Fig. 1 is a sectional plan view and Fig. 2 is a sectional side elevation of a combined latch and lock of a kind used on automotive vehicles and incorporating the invention; Figs. 3 and 4 are transverse sections on the respective lines 3—3 and 4—4 of Figs. 1 and 2; Figs. 5 and 6 are sections on the lines a—a of Figs. 1 and 2, the respective views being taken as though looking in the direction of the arrows 5 and 6 that are associated with said lines, and Fig. 7 is a perspective view of one of the electrical heating elements.

The casing of the latch (which latch may be of any approved type) is designated 1, and it is installed in the usual way in the door 2. In Figs. 1 and 2 a fragment of the door is indicated in dotted lines except the outer panel 3 that is shown in section. The latch operating handle is designated 5, and the inner end of the cylindrical shank 6 thereof is inserted through a hole in the panel 3 beyond which it is reduced in diameter at 7, providing an annular shoulder 8. Beyond the part 7 the shank is further reduced to provide a terminal portion 9 that has the usual operative connection with the latch bar 10 so that when the handle is rotated under normal operating conditions it will retract the latch bar and release the door. These latch features are no part of my invention and accordingly it is deemed unnecessary to specifically show and describe them. It may be explained, however, that in the type of latch shown the latch handle is held in place by a shouldered screw 11 that is inserted through an opening on the inside of the door and is threaded into a tapped hole in the inner end of the shank.

The handle has a bore 12 extending axially of its shank 6, the same being enlarged at its outer end to provide a chamber 13 that is counterbored at 14. A cylinder lock 15 occupies said chamber, the same having a circular enlargement at its outer end that is accommodated by the counterbore 14. An extension 16 of the lock has a working fit in the bore 12 and terminates short of the inner end of the bore. An eccentric stud or crank pin 17 projects from the inner end of the extension 16 into a vertical slot 18 of a locking bolt 19 that is slidable in a transverse opening in the part 7 of the shank. The base portion 20 of a keeper 21 is attached, as by rivets 22 (Fig. 3), to the front surface of the latch casing 1, the body portion of the keeper being semi-cylindrical and embracing one side of the part 7 of the shank. The keeper is provided with a slot 23 for the reception of one end of the bolt 19, said slot being elongated in a vertical

direction, as clearly shown in Fig. 3, in order to permit a limited movement of the operating handle in a counter-clockwise direction when the bolt is in locking condition. This limited movement of the handle is ineffective to release the latch.

The lock 15 is retained within the chamber 13 by a pin 25 that is projected through a hole in the part 7 of the shank tangent to and slightly intersecting the bore 12 and occupying an annular groove 26 of the lock extension 16. The pin 25 also holds in place upon the reduced part 7 of the shank a disk 38 of insulating material, within the front face of which is inlaid a segmental contact member 31 (Fig. 6). Thus, the disk 38 is secured against rotation to the shank of the operating handle, and when the handle is turned in a counter-clockwise direction as previously explained it will cause one end of the contact member 31 to override and bear upon a contact member 32 (Fig. 5) that is set within the rear face of a disk 33 of insulating material that is shown as applied to the inner surface of the door panel 3 and held fixed with respect thereto by screws 34 that pass through holes in the panel and are threaded into an escutcheon 35 that surrounds the shank 6 outwardly of the panel. The contact members 31 and 32 constitute the make-and-break device or switch that controls the supply of current to the heating means of my invention, as will hereinafter more fully appear.

The tumblers 38 of the cylinder lock 15 are adapted to be projected into one or the other of diametrically opposed recesses 39 that are formed in the handle and open into, and extended longitudinally of, the chamber 13. Intermediate the recesses 39, and also opening into the chamber 13 and extending some distance beyond the inner end thereof, are other recesses or channels 42 within which are fitted heating elements designated generally by the reference numeral 43 and one of which is shown in perspective in Fig. 7. Each heating element comprises a body 44 of suitable heat conducting insulating material, desirably of the highly compressed, very hard, cementitious kind commonly used in electrical heating appliances, said body being segmental in cross section and encasing an electrical resistor 45, a terminal whereof is exposed at 46 through the outer surface of the front end of the body 44. A lead wire 47 is connected to the opposite end of the electrical resistor and is insulated throughout the greater portion of its length. The insulated portions of the lead wires 47 are extended rearwardly through bores of the shank 6 that open through the shoulder 8 in register with holes in the disk 38 through which the ends of the wires are extended. Rearwardly of the disk 38 the terminals of said wires have electrical connection with the contact member 31, desirably through rivets 50 that hold said member in place and to the inner ends of which the wires are soldered. Current is conducted from a suitable source, as from the battery of the vehicle, to the contact member 32, by a conductor 51 that is shown as having its end soldered to a rivet 52 by which the contact member 32 is fastened to the disk 33.

In case a thin film of lubricant on the tumblers 38 of the lock 15 congeals from exposure to low temperatures sufficiently to obstruct movement of the tumblers; or moisture within and about the locking mechanism freezes and prevents normal operation thereof, the handle 5 may be

turned in a counter-clockwise direction to engage the contact member 31 with the contact member 32 thereby to permit current to flow from the source (not shown) through the wire 51, contact members 32 and 31, lead wires 47 and resistors 45 to where the circuit is grounded through the terminals 46 of the resistors that are in contact with the metal handle. As long as the handle is held in a position to maintain the contact members in engagement with each other, current will flow through the resistors 45 and as they become heated their elevated temperature is transmitted to the locking mechanism thereby to soften the lubricant or melt the ice and release the tumblers so that they will respond in a normal way to the insertion of the key which serves to retract the tumblers from the recess 39 and permit the lock cylinder, with its extension 16, to be rotated by means of the key through 180° or until the tumblers are in register with the other recess 39. The rotation of the lock is limited to 180° by a pin 55 that projects from the wall of the recess 13 radially into a segmental notch 56 in the rear end of the lock cylinder. When the lock is thus rotated the eccentric stud 25 or crank pin 17 shifts the bolt 19 to its unlock position in which it is withdrawn from the slot 23 of the keeper 21. With the operating handle thus released, it may be given a normal turn to retract the latch bar 10 and release the door.

Although I have shown and specifically described my invention as incorporated in a cylinder lock associated with a vehicle door latch of a certain type, it is to be understood that this is by way of illustration only and that the invention is applicable to locks of different kinds and environments. For example, the invention has marked utility in connection with boxes that enclose out-of-door telephones, as police and taxicab call boxes, etc.

Also, any approved type of heating element may be substituted for the embedded kind hereinbefore described, according to the nature and requirements of the construction at hand.

Further, in the broader aspect of the invention, what is herein shown as the latch handle may be regarded the lock housing; the invention being susceptible to all forms and variations falling within the scope of the appended claims, and where the term "latch bolt" is used in the claims it is intended to cover any equivalent holding means or element.

Having thus described my invention, what I claim is:

1. In combination, a housing having a cylinder chamber and opposed recesses opening into the same and extending longitudinally thereof, a cylinder lock plug having tumblers and rotatable in the chamber, the tumblers whereof cooperate with said recesses, the housing being provided with channels intermediate said recesses, electrical heating elements occupying said channels, an electric circuit including said heating elements, a switch in said circuit, and a locking element having operative connection with the lock plug.

2. In combination, a housing having a cylinder chamber and abutments spaced apart circumferentially thereof, a cylinder lock plug having tumblers and rotatable in the chamber, the tumblers whereof cooperate with said abutments, the housing being provided with a cavity adjacent said chamber, an electrical heating element occupying said cavity, an electric circuit including said heating element, a switch in said circuit, and a

- locking member having operative connection with the lock plug.
3. In combination with a latch including, a latch bolt and a movable operating member, locking mechanism governing the actuation of the latch bolt by said member, electrical heating means comprising an electrical resistance element and a mass of heat conducting electrical insulating material surrounding the same for heating the locking mechanism, the same being in such relation to said mechanism as to melt a foreign substance congealed thereon whose solidified condition interferes with the operation of the mechanism an electric circuit including said heating means, and a make-and-break device in the circuit actuated by the latch bolt operating member, said member being capable of limited movement without effecting release of the latch bolt while the locking mechanism is in locking condition.
4. In combination with a latch including a latch bolt and a rotatable operating member therefor, a keeper with respect to which said member is movable, a locking bolt carried by the member for locking engagement with the keeper, the locking bolt and keeper being so constructed and related that the member is capable of limited rotative movement in a direction opposite that in which it is moved for the purpose of retracting the bolt and while the locking bolt is in effective position, a lock cylinder rotatably sustained by the operating member and having operative connection with said locking bolt, electrical heating means comprising an electrical resistance element and a mass of heat conducting electrical insulating material surrounding the same and arranged in heating relation to the lock cylinder, an electric circuit including the electrical heating means, a switch in said circuit comprising a contact carried by and movable with the latch bolt operating member, and a second contact wherewith said member has relative movement, the contacts being adapted to be engaged during the aforesaid limited movement of the latch bolt operating member.
5. In combination with a movable member, an instrumentality adapted to be actuated thereby when moved in one direction, locking mechanism governing the actuation of said instrumentality by said member, electrical heating means comprising an electrical resistance element and a mass of heat conducting electrical insulating material surrounding the same for heating the locking mechanism, an electric circuit including said heating means, and a make-and-break device in the circuit actuated by movement of said member, the member being capable of movement in a direction opposite to that aforesaid to actuate said device while said mechanism is in locking condition.
6. In combination with a latch including a latch bolt and a tubular rotatable latch bolt operating handle, a cylinder lock plug having tumblers and rotatable within the bore of the latch bolt operating handle, the same governing the actuation of the latch bolt by the handle, the handle having abutments wherewith the tumblers of the cylinder lock plug cooperate, an electric heating means comprising an electrical resistance element and a mass of heat conducting electrical insulating material surrounding the same, said heating means being housed within the handle in such relation to the lock plug as to melt a foreign substance congealed in or upon the same, a contact member movable with the latch bolt operating handle and having electrical connection with the heating means, a second contact member with respect to which the latch bolt operating handle is rotatable and wherewith the first mentioned contact member is adapted to be engaged when the handle is rotated while the lock plug is in condition to prevent actuation of the latch bolt, and an electric circuit including said contact members and the heating means.
